PORTABLE ELECTRIC LAMP

Filed Jan. 14, 1928

FIG 2

FIG 1

INVENTOR.
WILLIAM BURNETT JR
BY
Wallace Brown
his ATTORNEY

UNITED STATES PATENT OFFICE

WILLIAM BURNETT, JR., OF MARION, ILLINOIS, ASSIGNOR TO MODERN COAL BURNER CO., OF CHICAGO, ILLINOIS, A CORPORATION OF ILLINOIS

PORTABLE ELECTRIC LAMP

Application filed January 14, 1928. Serial No. 246,701.

The present invention relates to portable electric lamps operated by a battery and adapted to be either suspended from some support or to be carried in the hand.

The special use for which the present electric lamp has been designed is for use as a safety lamp in mines and the like places, where there is danger of igniting explosive gases if an open flame or spark is permitted to come into contact with the gases. It has been generally employed as what is known as a "trip-lamp" and is attached to the edge of a mine car to indicate the presence or advance of said car in said mine, and as a warning to others of its presence or movement in such mine. This electric lamp may also be removed from said car and carried in the hand, if desired at any time.

One of the objects of the present invention is to provide a safety lamp adapted to be easily and quickly suspended from a mine car.

Another object is to provide such an electric lamp which shall be light in weight, and having a handle readily adapting it to be carried in the hand.

Another object is to provide such an electric lamp strong in construction, light in weight, simple as to parts and unbreakable even in case of accident.

With the above and other objects in view, which will more fully appear from the following specification, my invention relates to the combination of parts to provide the new and novel construction shown, and to produce the new and novel results outlined hereinafter. In the drawings forming part of this specification, I have shown one embodiment of my invention, and in said drawings, like numerals of reference refer to the same part throughout the various views, in which,

Figure 1 is a front elevation of said electric lamp as in use.

Figure 2 is a section view taken along the line $\alpha-\alpha$ of Figure 1.

The electric lamp shown in the accompanying drawings is especially adapted for use in mines, and other similar places, where there is liable to be explosive gases, which cause fire and explosion if they are permitted to come

into contact with the flame, or any spark from the lamp. For such uses, it is imperative that the lamp shall conform to the "safety regulations" established for operating lights in mines.

To accomplish this result and to guard against any accidental exposure to danger of fire which might be caused by accidental breakage of the said lamp or any of its parts, I have made the case 1 enclosing the parts

hereinafter described, of very heavy metal, with all of the openings securely covered by elements attached thereto by screw threads. There is an opening at the bottom of the case

to permit insertion of the battery and other parts, which opening is closed by a cover plate 3 attached to said case by passing two rods 5,

5 up through the case and through holes in the top 2, and securely held in place against the shoulder 4 at the bottom of the case by

means of nuts 7, 7 screw threaded upon the upper ends of said rods. A battery 8 is supported upon the cover plate 3 within the case

as shown, with its central terminal electrical- 70

ly connected with the case through the shelf 10 as shown in Fig. 2 and the other terminal electrically connected by a yielding connec- 75

tion 12 with the contact plate 10, mounted upon the shelf 9, and insulated therefrom by the insulation 11 inserted between said con-

tact plate and said contact plate and said shelf. As best indicated in Fig. 1, the ends of the plate 10 are provided with raised spring portions 12 and these spring portions

contact with the other terminal of the bat- 85

tery, thereby effecting a yielding electrical connection therewith. The said contact plate 10 is in turn connected by the insulated wire 13 with a second plate 14, as hereinafter de- 90

scribed. In the forward wall of the case, near the top, a lens opening 15 is provided, and this in turn is covered by a bezel 16 of extra heavy metal attached to the case by screws. Within said bezel, and resting with-

socket 18, mounted concentric with said lens, and having a reflector 19 extending forward therefrom, and in contact with the rear of the lens. Within the socket is mounted an electric light bulb 20 of any usual type. To make suitable connection between the lamp and the battery, the plate 14 is mounted between two insulating blocks 21 and 22 attached to the rear wall of the case by means of screws. The forward block 22 has an opening 23 therein in line with the stem of the socket 18, and adapted to permit the contact center of said socket to contact with said plate, closing the connection with one terminal of the battery through said plate 14, the wire 13, and the plate 10. The outer shell of the socket is connected with the case through the wire 24 in which in turn is attached to one of the screws 25 attaching the said blocks 21 and 22 to the wall of the case. A switch is usually mounted at some suitable portion of one of the lines to permit operation from without the case to disconnect said current when not in use.

At the rear of the case, attached near the top, I have provided the heavy U-shaped rod 26 to serve as a hook for mounting said lamp on the front, side or rear of a mine car, or for use as a handle to carry it in the hand, when desired. By placing suitable packing around the openings at the top, front, and bottom, and tightening the cover parts down tightly against said packing, it will be seen that said case may be closed air tight, and thus exclude all mine gas which might otherwise enter said case, and cause an explosion if coming into contact with the electric current or any sparks therefrom.

From the foregoing description, it will be seen that I have provided a very compact electric lamp, which is very strong and durable, and having but few parts to get out of order or become broken. It is small in size, light in weight, and can easily be attached or removed from the mine cars, or may be readily carried in one hand when desired. It is a perfect "safety-lamp", for the reason that all of the parts are contained within the case, and that this can be sealed perfectly against admission of any air or gas from without, and in use it has been found much preferable, and safer than any of the electric lamps now in use in the past.

Having thus described my invention, what I claim, and desire to secure by Letters Patent, is the following:—

1. A portable safety electric lamp, comprising a case, a cover plate for closing the bottom thereof, threaded rods extending from said cover plate through the top of said case, nuts on the ends of said rods, an electric battery within said case, a shelf above said battery dividing said case into two compartments, a contact plate adjacent one terminal of said battery, a yieldable connection between said terminal and said contact plate, a yieldable

connection between said case and the other terminal of said battery, a socket contact plate connected with said first contact plate, insulation material between said first plate and the case, insulation between said second plate and the case, a lamp socket in contact with said second plate, a connection between said case and the other terminal of said socket, a lamp in said socket, a reflector attached to said socket, and a lens in front of said reflector, substantially as shown and described. 75

2. A safety electric lamp for mines and the like places, comprising a metal case open at the bottom, a closure for said bottom having threaded rods extending through the top of said case, a U-shaped handle, a lens in the front of said case, a bezel surrounding said lens, a reflector adjacent said lens within said case, a lamp socket attached to said reflector, an insulated plate for contact with one terminal of said socket, a wire extending to the case from the other terminal of said socket, a battery within the case, one terminal connected with the insulated plate aforesaid, and the other with the case, substantially as shown and described. 90

3. A safety electric lamp comprising a metal case open at its bottom and separated into two compartments by a shelf, a handle on the exterior of said case; a closure for said bottom; a plate on said shelf insulated therefrom; a yieldable connection adapted to connect one terminal of a battery to said plate; a second plate on the lower side of said shelf and connected thereto; a second yieldable connection between the other terminal of said battery and said second plate; a lamp socket, reflector and lens in the upper compartment of and substantially within said case; a socket terminal contacting plate non-conductively connected to said case disposed rearwardly of said socket, a connection between the other terminal of said socket and said case, and a guard on the exterior of said case protecting said reflector and lens. 100

In testimony hereof I have signed the foregoing specification.
